ADSORBER CARTRIDGE AND RETAINER
CONSTRUCTIONVal J. Burke, Los Angeles, Calif., assignor to Burke and
Company, Los Angeles, Calif., a corporation of CaliforniaFiled May 27, 1963, Ser. No. 283,440
2 Claims. (Cl. 55—387)

This invention relates generally to air purification and filtration equipment, and more specifically is directed to improvements in cartridges containing adsorbent material and in retainers mounting such cartridges.

In accordance with a preferred embodiment of the invention hereinafter described and illustrated in detail, there is provided a retainer consisting of a hollow, generally rectangular frame made of sheet metal or equivalent material. A typical retainer may be 24 inches square, with the side walls extending about 12 inches in depth, although it will be understood that these dimensions may be varied as desired for particular installations. A plurality of such retainers may be mounted in adjacent rows and columns forming an array of any desired size for the air passage or chamber in which the array is installed.

On the inwardly directed opposed faces of the side walls of the retainer, there are cartridge-mounting means providing a plurality of grooves inclined slightly to the horizontal and extending generally from the front to the rear of the retainer. The grooves in each side wall are arranged in a zigzag configuration from top to bottom, and each groove is aligned with a corresponding groove on the opposite side wall.

Air purifying material of known type, such as activated carbon or the like, is carried in cartridges having perforated walls permitting air flow therethrough. Opposite end portions of each cartridge are received in a pair of grooves in opposite side walls. The cartridges may be easily slid into place from the front of the retainer and are held in place at the front by suitable removable means, desirably including a plurality of transversely extending junction strips and a pair of laterally spaced vertically extending latch bars selectively attachable to the retainer side walls. In the rear the cartridges are similarly held in place.

For maximum efficiency of the adsorbent material contained within the cartridges, it is desirable that such material be compacted as little as possible. In the present construction, compaction of the adsorbent material is minimized both by reason of the relatively slight inclination of the cartridge-supporting grooves of the retainer, and also by the internal construction of the cartridge itself. Thus, within the cartridge there are provided one or more partition strips extending virtually the entire length of the cartridge and thereby, in effect, dividing the interior of the cartridge into several smaller chambers. By this construction, there is very small static pressure upon even the lowermost granules of adsorbent material within each of the cartridge chambers. The cartridges include suitable openings and removable closure means therefor to facilitate periodic removal of the adsorbent material for replacement, recharging or the like.

The construction of the present invention is advantageous also in providing for either full detention or partial detention of the air passing therethrough, at the option of the user. Thus, any one or more of the plurality of cartridges carried by a single retainer may be

2

removed to provide partial detention, or all cartridges may be mounted in place for full detention.

Accordingly, it is a principal object of the present invention to provide a novel retainer and cartridge construction for air filtration equipment. Additional objects are to provide, in such construction, a generally rectangular retainer having an open interior and means mounted upon opposed side walls for removably carrying adsorbent cartridges; to provide, in such construction, means facilitating the insertion and removal of one or all cartridges from the retainer, as desired; to provide, in such construction, cartridges wherein compaction of the adsorbent material carried within the cartridge is minimized; to provide a very large expanse of adsorbent material 10 for air passage therethrough within a relatively small retainer; and for other and additional purposes as will be understood from a study of the following description of a preferred embodiment of the invention taken in connection with the accompanying drawing in which:

20 FIG. 1 is a perspective view of a retainer and ten cartridges mounted therein in accordance with the present invention.

25 FIG. 2 is a sectional view on a somewhat enlarged scale taken on arrows 2—2 of FIG. 1, with the third and fourth cartridges and the front air seal strip therebetween removed for clarity of illustration.

FIG. 3 is a fragmentary sectional view taken on arrows 3—3 of FIG. 1.

FIG. 4 is a fragmentary sectional view taken on arrows 4—4 of FIG. 2.

FIG. 5 is a fragmentary sectional view taken on arrows 5—5 of FIG. 1.

FIG. 6 is a perspective view of a cartridge with portions of the outer wall broken away.

35 FIG. 7 is a fragmentary sectional view on an enlarged scale taken along the arrows 7—7 of FIG. 1.

Referring in detail to the drawing, there is indicated generally at 10 a retainer in accordance with the present invention consisting of a hollow square defined by left 40 and right vertically extending opposed side walls 12 and 14 and horizontal upper and lower walls 16 and 18. The walls are desirably made of sheet metal or material of equivalent characteristics, and two adjacent walls, as 12 and 16, may be provided at their front edges with rearwardly turned lips 13 and 17 respectively for interengagement with edges of adjacent retainers when arranged in rows and columns to form a multi-retainer array.

On the inner faces of the side walls 12 and 14, there are provided means for receiving and supporting adsorbent-containing cartridges. In the present illustrative embodiment of the invention, such means include a pair of matrix plates or strips fastened as by adhesive or the like to the inner faces of the side walls, the matrix plates being indicated generally at 22 and 24 respectively. The 55 matrix plates may be economically formed of thin sheet plastic material configured as hereinafter described, and desirably the material is so chosen to permit at least some resiliency or yieldability, for reasons later appearing. Each matrix plate is configured to provide a series 60 of grooves 32 for receiving end portions of cartridges arranged in zigzag relation from top to bottom of the retainer, the grooves being separated by raised portions or lands. Thus, with particular reference to matrix plate 24 as seen in FIG. 2 upper and lower lands 26 and 28 are desirably in the form of right triangles, and intermediate lands 30 are in the form of isosceles triangles. The apex angles of the isosceles triangles are desirably no more than about 30° and preferably of the order of 20°, so that the grooves between successive lands are inclined 65 to the horizontal at angles no greater than 15° and prefer-

ably about 10°. The matrix plates are so mounted upon their respective side walls that the grooves of one plate are in horizontal alignment with the grooves of the opposite plate. In the present embodiment of the invention, intended to mount a maximum of 10 cartridges, there are accordingly 10 such pairs of aligned grooves 32.

The cartridges used in accordance with the present invention are identical with one another, and their construction will be understood by reference to the general showing in FIG. 6, supplemented by the detailed showings in FIGS. 4 and 7. As best appears in FIG. 6, the cartridge indicated generally at 40 includes a pair of major faces, upper face 42 and lower face 44, in parallel planes spaced apart by a distance small relative to a dimension of either of the major faces. The cartridge may be economically manufactured by wrapping a sheet of perforated metal cloth or the like around a pair of end members, desirably in the form of U-shaped channel strips indicated generally at 46 and 48. One of the channel strips, as 46, is provided with one or more filler openings 50 formed in the central web 52 of the channel. The cartridge is desirably strengthened longitudinally and also divided into a plurality of internal chambers by one or more partition strips, there being two such strips 54 and 56 in the cartridges of the present invention. The strips extend at least a substantial portion of the length of the cartridge and are joined as by tack weld or the like to the channel member 48 at one end and may terminate near the other end at 55 and 57 respectively, spaced somewhat from the channel 46 in which are located the filler openings 50. The partition strips 54 and 56 extend between the upper and lower faces 42 and 44 of the cartridge, so that the interior of the cartridge is divided into a plurality of at least partially isolated compartments, three in the present illustration, separated except for the gap between the ends 55 and 57 and the channel 46. Closure means in the form of resilient plug members 60 are desirably provided within the channel 46 spanning the filler openings 50 and made of rubber or other easily compressible substance, so that they are held within the channel and close the openings by frictional engagement with the side walls 51 and 53 of the channel. The cartridge walls include, in addition to the major faces 42 and 44, side walls 62 and 64, and desirably all walls of the cartridge constitute a single sheet of perforated metal cloth wrapped around and fastened as by tack welds 65 to the channel members 46 and 48 and to strips 54 and 56. The walls or faces are provided with a multiplicity of perforations 66 for air passage therethrough, small enough in size to retain adsorbent material 68 within the cartridge.

In full detention operation of an air filter in accordance with the present invention, it is desirable to prevent any air from by-passing the cartridges during its flow through the retainer. For this purpose there are provided across the rear face of the retainer 10 a series of fixed junction strips constituting air seals between adjacent cartridges, and a similar, but removable, series of such strips is provided across the front face of the retainer. Additionally, as will be seen in FIG. 2, the upper wall 16 may be provided at its rear edge with a downwardly depending lip 15 against which the upper end of the uppermost cartridge abuts when the cartridge is in place. Similarly, the lower wall 18 may be provided with an upwardly extending lip 19 against which the lower end of the lowermost cartridge may abut.

The junction strips extending across the rear of the retainer previously mentioned are indicated generally at 80 in FIGS. 2 and 3 and are fixed at either end to the side walls 12 and 14 by suitable means, such as the weld 82 seen in FIG. 3. Similar junction strips 80 extend transversely across the front face of the retainer, and are removable for permitting insertion and removal of the cartridges as desired. With particular reference to FIG. 7, the junction strip 80 is desirably in the general

form of a T formed of a single piece of metal folded to form a central tongue portion 90 and two outwardly extending flange portions 92 and 94. From this construction it will be seen that air movement through the retainer is virtually impossible without passing through one of the cartridges 40. The air seal strips 80 in the front of the retainer are held in place between adjacent converging cartridges as seen in FIGS. 2 and 7 by a pair of laterally spaced vertically extending locking bars, L-shaped in section, indicated generally at 96 and 98, each removably fastened to the side walls 12 and 14 respectively, as by spring-loaded bayonet fasteners indicated generally at 100 carried by the locking bar flange 102 and selectively engageable (see FIG. 5) with slotted brackets 104 fixed to the retainer side walls.

The air seal junction strips 80 including tongue 90 between adjacent cartridges assure full detention operation when all cartridges are in place. When partial detention operation is desired, one or more of the cartridges can be easily removed so that only part of the air passing through the retainer is treated by the adsorbent material within the cartridges remaining in the retainer. It is further to be noted that, by reason of the relatively small angle of inclination between the plane of a cartridge and the horizontal, in cooperation with the partition strips 54 and 56 within the cartridges, the adsorbent material within the cartridge is not subjected to any substantial pressure from the weight of other adsorbent material within the same compartment or chamber and compaction of the adsorbent is hence minimized.

Moreover, the cartridges may be easily slid into or out of position in the retainer, but once in position, the air seal tongue 90 between adjacent cartridges serves to spread the cartridges slightly apart against the yielding resiliency of the matrix plate lands 30. With the cartridges thus snugly held in place, the assembly is free of rattles or other noises in operation, and prevention of unintended by-passing of air is further assured.

Modifications and changes from the preferred form of the invention heretofore illustrated and described are within the contemplation of the invention, and all such modifications and changes not departing from the spirit of the invention are intended to be embraced within the scope of the appended claims.

What is claimed is:

1. An air filter assembly comprising:
a generally rectangular hollow retainer extending in depth longitudinally of the path of air flow and including horizontally disposed upper and lower walls and laterally spaced vertically extending side walls; means forming grooves on the inwardly directed faces of the side walls including a series of aligned pairs of grooves, each groove being slightly inclined to the horizontal, successive aligned pairs of grooves from top to bottom being oppositely inclined in zigzag relation;
a thin adsorbent filter element of elongated rectangular shape having opposite end marginal portions slidably received in each pair of grooves and extending longitudinally across the width of the retainer in a plane determined by the groove inclination, each of said filter elements comprising a cartridge having perforated walls and containing granular adsorbent material therein, and a partition strip extending longitudinally within the cartridge intermediate the sides thereof for dividing the interior of the cartridge into at least partially isolated compartments and thereby to minimize compaction of the adsorbent material; and means carried by the retainer for removably holding said elements in assembled relation in their respective pairs of grooves, including removable junction strips extending the width of the retainer and provided with tongue portions projecting inwardly between marginal side portions of adjacent filter elements.

2. An adsorbent-containing cartridge for use in an air filter and adapted for air passage therethrough comprising:

a container of perforated sheet material having a pair of parallel major rectangular faces spaced apart by a distance small relative to a dimension of said faces;

a quantity of compactable granular adsorbent material within the container;

and a partition within the cartridge extending between and attached to the material of said faces, the partition extending longitudinally over substantially the length of the cartridge intermediate the sides thereof whereby to divide the interior of the cartridge into substantially isolated compartments and thereby to minimize compacting of said adsorbent material when the cartridge is inclined across its width.
